(57) **CLAIM**

The ornamental design for a vehicle display system, as shown and described.

DESCRIPTION

FIG. 1 is a front elevational view of the vehicle display system of the present invention;

FIG. 2 is a rear elevational view of the vehicle display system of FIG. 1;

FIG. 3 is a left side elevational view of the vehicle display system of FIG. 1;

FIG. 4 is a right side elevational view of the vehicle display system of FIG. 1;

FIG. 5 is a top plan view of the vehicle display system of FIG. 1;

FIG. 6 is a bottom plan view of the vehicle display system of FIG. 1; and,

FIG. 7 is an enlarged front elevational view of just the keypad device.

The broken lines showing of letters in FIGS. 1, 6 and 7 are for illustrative purposes only and form no part of the claimed design.
